CENTRIFUGAL SEPARATING MACHINE.

Application filed January 7, 1927, Serial No. 159,614, and in Sweden September 10, 1926.

In the well known type of drums for centrifugal separating machines, in which there are conical plates or discs with holes in the conical parts thereof for the introduction 5 and distribution of the incoming supply of liquid, it is of great importance, in order to obtain the highest separating efficiency of the drum, that these holes should be located so that the distances from them to the inner 10 and outer edges of the plates are in a predetermined relation to the proportions and properties of the components in the liquid mixture to be separated. This is illustrated by Figures 1 and 1^a of the accompanying 15 drawings each figure showing one half of two adjacent plates a_1 and a_2 in sectional elevation. At the left hand side in Figure 1 the inlet holes b_1 , for the liquid to be separated, are situated at a relatively short distance from the inner edges of the plates and in Figure 1^a at the right hand side the inlet 20 holes b_2 are nearer to the outer edges of the plates, the arrows in each figure indicating the main direction of the currents which 25 occur when two liquids of different specific gravities are being separated. The specific gravity of the liquid radially outwards of the holes should obviously be higher, and that of the liquid radially inwards of the 30 holes should be lower than that of the original (incoming) mixture. If a complete separation takes place, the liquid discharged from the outer edge should consist of heavy components only and the discharge from the 35 inner edge should be free from such components.

If the liquid mixture to be separated contains a high percentage of heavy components or if it is most important that the separated 40 heavy components should be as free as possible from lighter ones, the unseparated mixture must be introduced between the plates near to their inner edges, *i. e.* the drum should be of a construction such as is shown 45 in Figure 1, because the distance the greater proportion of the mixture (the heavy components) must be caused to traverse by centrifugal force is much longer than that which much be traversed by the smaller portion thereof. A typical example of this 50 is the separation of cream and milk, where as a rule about 90% heavy components (skim milk) are separated, which should contain the smallest possible amount of light ingredients (fat).

In converse cases, for instance, the separation of oil and water where the proportion of water usually does not exceed 10% and where it is more important to obtain water-free oil than oil-free water, the inlet 60 holes should be situated nearer to the outer edges of the plates as shown in Figure 1^a. In some instances, however, a combination of these arrangements must be used, for instance, for a mixture of 10% oil and 90% 65 water, especially if both water-free oil and oil-free water are required. The mixture should first be run through a drum constructed as shown in Figure 1 in which the separated water becomes practically free 70 from oil and it can therefore be discharged anywhere or be used again, but the separated oil will contain a slight percentage of water, which latter mixture must then be treated in a drum constructed as shown in Figure 75 1^a.

From the above it will be understood that it is necessary for different purposes to use centrifugal drums differing in this respect in order to obtain the best separating results. 80

The present invention has for its object an arrangement by which a centrifugal drum can be adjusted in a simple manner so that the position of the inlet for the liquid into the conical plates will be always the most 85 suitable for any particular purpose, thus the same drum can be used for very different purposes.

According to this invention means are provided for varying the position of the inlet from the distributor to the spaces between the conical plates to suit the different purposes for which the drum is used.

The invention is illustrated by Figures 2 to 6 of the accompanying drawing, in which different arrangements are shown, Figures 2 and 3 show the lower parts of two centrifugal drums in sectional elevation, Figure 4 is a plan view of the conical intermediate plates shown in Figures 2 and 3 respectively and Figures 5 and 6 are plan views of the arrangements shown in Figures 2 and 3 respectively, but with only the bottom plate in place (all other intermediate plates being removed).

In Figures 2 to 6, 1 is the shell of the drum, 2 a receiver and distributor for the supply of liquid between which distributor and the bottom of the shell 1 are channels 3 for conveying the incoming (feed) liquid 110

from the centre of the drum to holes or openings 4 in said distributor through which holes the liquid is led in between conical intermediate plates 5 formed with holes 6 corresponding with the holes 4 in the distributor 2. The holes 6 form vertical channels through which the feed liquid is led and whence it is distributed between the conical intermediate plates 5. 7 is a bottom plate 10 with holes or openings 8.

In Figures 2, 3 and 4 are shown plates 5 provided with radially elongated openings 6 and the distributor 2 shown in Figures 2, 3, 5 and 6 has corresponding openings. 15 In Figures 2 and 5 the bottom plate 7 is formed with series of holes 8 angularly displaced and with their centres situated on a spiral or the like at different distances from the drum centre in such a way that 20 all the holes at the same radial distance correspond with portions of the elongated holes in the plates 5 and in the distributor 2. This bottom plate 7 can be placed in different angular positions relatively to the distributor 2 so that any hole of each series 25 registers with a portion of an opening in the distributor 2 and plates 5, thus enabling the positions of the inlet to the plates 5 to be varied according to the different angular 30 positions of the bottom plate 7.

In Figures 3 and 6 is shown a bottom plate 7 formed with spirally elongated openings 8 corresponding in number with the radially elongated openings in the distributor 2 and 35 the plates 5. This bottom plate 7 can be turned on the distributor 2 and the positions of the inlets from the distributor 2 to the intermediate plates 5 can, consequently, be varied according to the different angular 40 positions of the bottom plate 7.

Although only the above arrangements are shown in the drawings it is obvious that other modifications can be made within the scope of the invention. Thus, the holes in 45 the intermediate plates 5 and in the distributor 2 can be arranged in series on several radial lines instead of being elongated or they can be made like the holes 8 in the bottom plate 7 in Figures 2 and 5 and in

Figures 3 and 6, but in the latter event the 50 holes in the bottom plates 7 must then be arranged as in the intermediate plates 5 in the respective figures, or the holes in the plates, the distributor and bottom plate could all be spirally situated or the like or 55 they could consist of spirally elongated openings, provided only that the openings in the bottom plate do not all or entirely correspond with the openings in the distributor and the plates, etc. 60

We claim:—

1. A centrifugal machine for the continuous separation of two or more liquids of different specific gravities, comprising a drum, intermediate conical plates spaced 65 apart in said drum, said conical plates having apertures in the conical parts thereof, adapted for the introduction and distribution between said plates of an incoming supply of liquid, a distributor formed with openings constituting an inlet to the spaces between said conical plates adapted to receive and distribute the incoming liquid to 70 said apertures, and a bottom plate provided with apertures for cooperation with the openings in said distributor to vary the position of said inlet according to the required liquid separation upon rotation of the bottom plate. 75

2. A centrifugal drum as claimed in 80 claim 1, in which the intermediate plates and the distributor are formed with groups of apertures radially in line, said drum being provided with a bottom plate having a series of apertures situated at different 85 distances from the drum center and adapted to be placed in different angular positions, whereby apertures at the same radial distance from the drum center will register with the apertures in the intermediate 90 plates and the distributor and the positions of the inlets from the distributor to the spaces between the intermediate plates can be varied by placing the bottom plate in different angular positions. 95
